(54) **LEVER POWER, SAWING, &C. , BY**

(76) Inventor: **Jeremiah Walker**

Jeremiah Walker, Phillips, Maine
Letter Patent

The Schedule referred to in this Letter Patent and making part of the same containing a description in the words of the said Jeremiah Walker himself of his improvement in the lever ^{power} machine for sawing and other purposes.

To all to whom these presents shall come. Whereas it is known that I, Jeremiah Walker of Phillips in the County of Edmund and State of Maine have invented a new and useful machine called a lever power machine for sawing and other purposes and that the following is a full and exact description thereof. In the first place there is a frame about five feet long two and a half feet wide and two feet high which is constructed of as many pieces of timber and of such dimensions as will render it firm and strong; near one end of this frame there is a circular saw which is hung upon an iron shaft which rests upon the top of the frame and goes quite round it; the saw is placed toward one end of the shaft, first within the frame toward the other end of the said shaft there is a pulley. The shaft is kept in its place by iron plates placed over it and secured down to the frame. near the other end of the frame there is another iron shaft running horizontally across the frame like the former which is kept in its place by iron plates secured to the frame in the same manner as the first mentioned. toward one end of this shaft and another opposite to the pulley on the iron shaft there is a large drum wheel and a flat leather band going around them and the pulley connects them together. this shaft containing the drum which is called the crank shaft, because it is so bent as to make three cranks, two within the frame a little to the left of the drum and the other at the end outside the frame. The operation is performed by means of two levers as follows viz. one of the levers is long, the other short with a weight attached to its outer end which acts as a ful-

a little way from the frame both of these levers at their inner ends are
fastened to one of the bottom pieces of the frame below the saw shaft
by means of joints formed of loops and staples. There is also an iron
staple in each of these levers directly under the crank shaft
these two iron loops are passed around the two middle cranks at their
upper ends and passing down in a perpendicular direction a
little below the cranks and looped into the staples in the lever
so as to connect the cranks and the levers together. This being done
the drum wheel is started in the direction which it should go
by hand, then the levers commence their up and down motion
when the outer end of the long lever which is operated by hand is
raised, up the short lever containing a weight on its outer end
comes down and each lever carries its own crank along with it
thus by the simple operation of the long lever the whole ma-
chine is put in motion and by means of the drum and pulley
the circular saw is carried around with great rapidity and
sureness and saving a valuable purpose in sawing many sorts
of wood and timber. To the third crank which is situated
outside of the frame by the help of suitable gear work there may
be attached a cross cut saw as also sawing implement for various
jobs. When two persons undertake to operate the machine two
long levers are to be used & the weight abovementioned is to
be suspended with. — Dated at Phillips, aforesaid this
3rd day of November anno Domini 1836.
